UNITED STATES PATENT OFFICE.

JOHN R. HARLOW, OF AUBURN, NEW YORK.

SPOON-BAIT.

SPECIFICATION forming part of Letters Patent No. 734,708, dated July 28, 1903.

Application filed November 10, 1902. Serial No. 130,714. (No model.)

To all whom it may concern:

Be it known that I, JOHN R. HARLOW, of Auburn, in the county of Cayuga, in the State of New York, have invented new and useful 5 Improvements in Spoon-Bait, of which the following, taken in connection with the accompanying drawings, is a full, clear, and exact description.

This invention relates to improvements in 10 spoon-baits, and refers more particularly to the means for attaching the hook to the spoon.

The objects of these improvements are, first, to reduce the cost of assembling and finishing the parts, and, second, to afford a more permanent and reliable connection between the 15 hook and spoon.

In the manufacture of spoon-baits of the class described the usual practice is to solder the shank of the hook to the spoon, and it 20 therefore becomes necessary to heat the metal to such a degree as to materially weaken it at its junction with the hook, where the strain is usually the greatest. Furthermore, this method of soldering the parts necessitates the 25 careful working of the solder in the joint and then blending or smoothing the solder with the contiguous surfaces of the spoon preparatory to plating and burnishing, and it is evident that when the hook is thus secured to 30 the spoon before final finishing or burnishing this final operation becomes difficult and requires careful manipulation to prevent the point of the hook from being caught in the buffer-wheel or fingers of the operator.

35 My invention is designed to obviate the use of solder and the difficulties of burnishing and finishing the spoon incidental to the securing of the hook to the spoon before the buffing and finishing of the spoon is complete 40 and at the same time produce a stronger spoon-bait without detracting from its pleasing appearance.

To this end the invention consists in combining and uniting the spoon and hook, as 45 hereinafter fully described, and pointed out in the claims.

Referring to the drawings, Figure 1 is a 50 face view of a spoon-bait embodying my invention. Figs. 2 and 3 are sectional views taken respectively on lines 22 and 33, Fig. 1, Fig. 3 being enlarged. Fig. 4 is a face view of the detached spoon.

Similar reference characters indicate corresponding parts in all the views.

In order that my invention may be clearly 55 understood, I have shown a spoon 1, a hook 2, and a swivel-head 3. The spoon 1 may be of any desired form or size, being usually formed of thin sheet metal of concavo-convex lengthwise and transverse section, and 60 is provided with opposite end and intermediate apertures 4, 5, and 6, the end having the aperture 4 being regarded as the head of the spoon and receives the swivel 3, which is linked in the aperture 4, while the 65 opposite end, having the aperture 5, may be designated as the trailing or hook end of the spoon to receive the shank of the hook. The intermediate aperture 6 preferably extends through the central body of the spoon 70 and preferably in direct line between apertures 4 and 5, which line forms practically the lengthwise axis or line of draft of the spoon and hook. The aperture 5 is formed in the upturned trailing end of the spoon and 75 is therefore substantially parallel and coincident with the lengthwise axis and receives the shank of the hook and holds the same from lateral displacement. The hook 2 may also be of any desired size proportionate to 80 the size of the spoon and is inserted through the aperture 5, with the hook projecting beyond the trailing end of the spoon and its shank extending inwardly along and upon the inner or concave face of said spoon and 85 provided with an aperture or eye 7, registered with the intermediate aperture 6. The means for securing the inner end of the hook in position preferably consists of a hollow stud 8, which is passed through the aperture 90 6 and eye 7 and expanded or riveted at its opposite ends to lock the parts firmly together. It is sometimes desirable to remove the hook from the spoon and substitute another of 95 different size or form or to substitute a new hook for one that has become bent or broken, and I therefore have shown the inner end of the stud 8 as screw-threaded to receive a threaded head or nut 9, the opposite end of said stud being expanded or upset to form a 100 head 10, engaged with the convex face of the spoon, while the walls of the eye 7 are impinged between the head or nut 9 and adjacent face of the spoon. After the nut is

properly adjusted the inner end of the stud is slightly expanded to firmly hold the parts in operative position without liability of becoming displaced while in use.

- 5 In the manufacture of my improved spoon-bait the spoon is first pressed or stamped to the desired form, the apertures 4, 5, and 6 being formed by the same or by one or more subsequent operations, and the whole spoon 10 is then plated, burnished, and finally finished before the hook is attached thereto. After this operation the hook is passed through the aperture 5, as shown in the drawings, and the eye 7 is registered with the aperture 6, 15 whereupon the hollow stud 8 is inserted in position and secured in the manner described, and after attaching the swivel-head 3 the device is ready for use.

It is evident from the foregoing description 20 that the main features of this invention consist in inserting the shank of the hook through an aperture in one end of the spoon and in providing a suitable stud for locking the end of the shank to the body of the spoon, and 25 various forms of hollow or solid rivets may be substituted for the threaded stud and nut without departing from the spirit thereof.

Having thus described my invention, what 30 I claim, and desire to secure by Letters Patent, is—

- 35 1. A spoon-bait comprising a spoon and a hook, each having an aperture, and means passed through the apertures to secure the spoon and hook together.
2. In a spoon-bait, a spoon having an aperture, a hook seated on the spoon, and a stud passed through the aperture and engaged with the hook to lock the parts together.
3. In a spoon-bait, a spoon, a hook seated 40 on the spoon and provided with an eye, and a stud passed through the eye and engaged with the spoon to lock the parts together.
4. A spoon-bait comprising a spoon and

hook each having an aperture, and a threaded stud passed through the apertures and provided with a nut for locking the parts together.

5 In combination with a spoon having an opening in one end, a hook having its shank inserted in the aperture, and a threaded stud 50 and nut securing the inner end of the shank to the spoon.

6. A spoon-bait comprising a spoon having end and intermediate apertures, a hook inserted in the end aperture and provided with 55 an eye registered with the intermediate aperture, and means passed through the intermediate aperture and eye to lock the parts together.

7. A spoon-bait comprising a spoon having 60 an aperture, a hook having its shank seated in the aperture and provided with an eye, and means passed through the aperture and secured to the spoon to hold the spoon and hook in fixed relation to each other.

65 8. A spoon-bait comprising a spoon having a central aperture, a hook having an eye at one end of its shank, and a tubular stud passed through the aperture and eye and expanded to hold the parts in fixed relation to 70 each other.

9. In a spoon-bait, the combination of a spoon having a pair of apertures one in advance of the other, a hook having its shank inserted in one of the apertures and provided 75 with an eye alined with the other aperture, and means passed through the eye and aperture alined therewith for securing the spoon and hook together.

In witness whereof I have hereunto set my 80 hand this 30th day of August, 1902.

JOHN R. HARLOW.
